UNITED STATES PATENT OFFICE.

CLARK WAY HARRISON, OF SUMMIT, NEW JERSEY.

TOBACCO-PIPE, CIGAR-HOLDER, AND CIGARETTE-HOLDER.

1,234,541.

Specification of Letters Patent. Patented July 24, 1917.

Application filed July 9, 1913. Serial No. 778,007.

To all whom it may concern:

Be it known that I, CLARK WAY HARRISON, a citizen of the United States, and a resident of the town of Summit, county of Union, and State of New Jersey, have invented certain new and useful Improvements in Tobacco-Pipes, Cigar-Holders, and Cigarette-Holders, of which the following is a specification, reference being made to 10 the accompanying drawings, forming a part thereof.

The invention relates to improvements in check-valves of tobacco-pipes, cigar-holders, and cigarette-holders, which prevent saliva 15 from the smoker's mouth entering the smoke channel. They are usually so arranged that the suction created by the smoker's mouth will open the valve against a spring or elastic, the latter effecting the closing of the 20 check-valve when the suction is discontinued. Previous designs have not proved practicable for many reasons; first, the mouth piece, carrying both the valve-stem and smoke channel, is so thick as to render 25 it uncomfortable when holding it between the smoker's teeth; secondly, the tendency of the valve to stick owing to the action of the tobacco juice and smoke on the bearings of the valve-stem and on the spring; thirdly, 30 there is no outside means to overcome by hand the sticking of the valve, fourthly, there is no convenient means for removing the valve for cleaning; fifthly, there is no means for preventing the heat and moisture 35 from affecting the spring; sixthly, there is no convenient means for adjusting the tension of the spring or elastic.

It is the chief object of my invention to devise improved means for overcoming the 40 many faults pertaining to known devices of this kind and with these ends in view, the invention consists of certain features of novelty in construction, combination and arrangement of parts by which the said object and certain other objects which will 45 hereinafter appear are attained, an example of which invention will now be described with reference to the accompanying drawings, the invention being more particularly 50 pointed out in the claims:—

In the said drawings, Figure 1 is a vertical sectional view of a tobacco pipe embodying this invention.

Fig. 2 is a similar section through A—B 55 taken on a plane at right angles to that of Fig. 1 and viewed from above.

Fig. 3 is a vertical sectional view of a tobacco pipe embodying a modification of said invention.

Like letters of reference indicate similar 60 parts in all the figures.

Referring first more particularly to Fig. 1 *a* designates the bowl of a tobacco pipe provided in the usual manner with a smoke channel *S* which conveys the smoke to a 65 mouth piece *b* in which there is located, at the end which enters the smoker's mouth, a check valve *c* which is so arranged that it will allow the exit of the smoke but will prevent the entrance of saliva from the 70 smoker's mouth.

In this particular form of the invention I employ in the mouth piece *b* two smoke channels *S*³ *S*⁴ (Fig. 2), the smoke being first conveyed through the channel *S* into 75 the chamber *v*, from which it is conveyed through the short vertical channels *S*¹ *S*² (Fig. 2) into the two channels *S*³ *S*⁴ of the mouth piece and then out through the check valve into the smoker's mouth. 80

d designates a valve stem arranged to slide back and forth in a bearing centrally located in the mouth piece *b* and located between and in approximately the same horizontal plane with the two smoke channels 85 *S*³ *S*⁴. One end of the valve stem carries the check-valve *c* and the other end protrudes from the opposite end of the mouth piece and carries a spring *e* (not shown in section), a nut *f*, and a cup-shaped piece *g* 90 the two latter being screwed on.

The two smoke channels *S*³ *S*⁴ are conveniently drilled partly from both ends of the mouth piece, first from the bowl end the straight portion is drilled to a point near 95 check valve, then the short angular portion is drilled from the other end after first drilling out the seat of the check-valve. The two screwed plugs *m*¹ *m*² serve two purposes, first to stop up the end of the smoke channels *S*³ *S*⁴ and to allow when removed the cleaning of the said smoke channels. 100

From the above description it will be seen that the spring *e* tends to hold the valve *c* in a closed position. Suction produced in 105 the smoker's mouth causes the check valve to open collapsing the spring *e* which bears against the mouth piece and against the nut *f*. The suction and resulting flow of smoke prevents saliva from entering the 110 smoke channel while the check valve is open. The moment the suction is discontinued the

spring *e* expands closing the check-valve, the seat and face of which can be ground if necessary.

It will be seen that by employing a bearing for the valve stem as shown I have reduced to a minimum the likelihood of tobacco juice and smoke causing the valve to stick.

By placing the valve stem in approximately the same horizontal plane as the smoke channel in mouth piece, it enables me to retain the proper capacity of smoke channel, the proper size and strength of valve stem, and the proper strength of the mouth piece itself, and at the same time keep the thickness of the mouth piece within such limits that it will not prove uncomfortable to the smoker when holding it between his teeth.

20 By placing the spring *e* where the smoke and juice and heat cannot come in contact with it the likelihood is eliminated of its becoming gummed up, rusting, or losing its temper and strength. By employing a valve stem that protrudes from the mouth piece, it becomes possible to open the valve by pressure of the finger while pipe is held in the smoker's mouth thus overcoming any sticking of the valve, and enabling the 25 smoker to blow air through the smoke channel to remove instantly an obstruction. By merely removing the cup shaped piece *g* and the nut *f* the valve and valve stem can be readily withdrawn from the mouth piece 30 for cleaning purposes.

By turning the nut *f* the tension of the spring *e* can be adjusted to a nicety. And it will also be seen that by turning the cup shaped piece *g* the limit of opening of the 40 valve can be adjusted.

It is obvious that I can attain the same object by employing only one smoke channel such as S^3 in the mouth piece or I can employ two valve stems placed in a common 45 horizontal plane with one smoke channel located between and in the same horizontal plane. In fact I do not limit my invention to any number of either.

It is also obvious that instead of a spring 50 *e* which is compressed when valve opens I could use a spring or elastic which is elongated when valve opens, as shown in Fig. 3. In this case one end of the spring or elastic could be attached to the bowl of the pipe or 55 to an extension of the mouth piece while the other end would be attached to the valve stem, or to the cup-shaped piece *g*. In the

latter case the functions of the nut *f* and piece *g* would then be reversed, piece *g* would permit of varying the tension of 60 spring or elastic and nut *f* would adjust the limit of valve opening.

In using my invention for a cigar holder or cigarette-holder the holder is substituted for the part containing the pipe-bowl and 65 made so as to preferably hold the cigar or cigarette at an angle inclined away from the smoker's face.

It is obvious that various other forms and modifications may be made without departing from the spirit and scope of my invention.

I claim as my invention:—

1. A tobacco pipe, cigar-holder, or cigarette holder having a check-valve in the end 75 of the mouth-piece to prevent saliva entering the smoke channel, the closing of the check-valve being effected by a spring or elastic located outside the smoke channel.

2. A tobacco pipe, cigar-holder, or cigarette-holder having a check-valve in the end 80 of the mouth-piece to prevent saliva entering the smoke channel, the closing of the check-valve being effected by a spring or elastic so located as to be in contact with the 85 outside air.

3. In a tobacco pipe, cigar-holder, or cigarette holder the combination of a check-valve in the end of the mouth-piece to prevent saliva entering the smoke channel, and 90 a valve-stem having its end, which is opposite the check-valve, extending to the exterior of the pipe-stem or holder.

4. In a tobacco-pipe, cigar-holder, or cigarette-holder, the combination of a check- 95 valve, a valve-stem, and two smoke channels in the mouth-piece, the valve-stem being located between the two smoke-channels and all in approximately the same horizontal plane.

5. In a tobacco pipe, cigar-holder, or cigarette holder, the combination of a smoke channel, a check-valve in the end of the mouth-piece to prevent saliva entering the smoke-channel, and a valve-stem movable in 105 a cylindrical bearing located alongside the smoke-channel and in approximately the same horizontal plane.

This specification signed and witnessed this eighth day of July, 1913.

CLARK WAY HARRISON.
